RADIO REMOTE CONTROL

David G. C. Luck, Oaklyn, N. J., assignor to Radio Corporation of America, a corporation of Delaware

Application January 31, 1939, Serial No. 253,889

13 Claims. (Cl. 250—2)

This invention relates to radio remote control and more especially to an impulse type of remote control which is not easily deciphered.

Numerous types of remote control by radio have been proposed. Controls of this type may be used in directing mobile vehicles such as aircraft. It is important that the control be suitable for operating a number of functions, be fast operating, be operable through interference and be not easily deciphered.

It is one of the objects of the invention to provide means for remotely controlling by radio.

It is another object to provide means for radio remote control in which simultaneous impulses are transmitted on two or more frequencies.

It is another object of the invention to provide means for remotely controlling by several radio impulses of short duration which are interlocked in effect.

A further object is to provide means for remotely controlling by radio a number of functions in any required order.

The invention will be described by referring to the accompanying drawings, in which

Figure 1 is a schematic diagram of the remote control transmitter,

Figure 2 is a modification of the transmitter,

Figures 3 and 4 are details of the transmitter,

Figure 5 is a schematic diagram of the receiver of the invention,

Figure 6 is a detail of the receiver, and

Figures 7 and 8 are sectional views of the key interlocking means.

Referring to Fig. 1, three snap keys or snap switches 1, 3, 5 are connected as follows: The first key 1 is connected to the first 7 and sixth 11 of six buffer stages. The second key 3 is connected to the second 13 and third 15 buffer stages. The third key 5 is connected to the fourth 17 and fifth 19 buffer stages. Three oscillators 21, 23, 25 are connected as follows: The first 21 is between the first and second buffer stages; the second 23 is between the third and fourth buffer stages; and the third is between the fifth and sixth buffer stages. The oscillators supply continuously currents of frequencies f_1 , f_2 and f_3 . By way of example, these frequencies may be 2, 2.01, and 2.02 megacycles per second.

The buffer stages are preferably thermionic tubes which are arranged to prevent currents from the oscillators being applied to the modulators 27, 29 during key-open periods. During key-closed periods, the oscillator currents are applied to the modulators through the buffer stages which are keyed.

The outputs of the second, fourth, and sixth buffer stages are applied to the first or No. 1 balanced modulator 27. The outputs from the first, third, and fifth buffer stages are applied to the second or No. 2 balanced modulator 29. The balanced modulators are both connected to a master oscillator 31 which supplies currents of frequency f_0 which, by way of example, may be 30 megacycles per second. The output of No. 1 modulator 27 is applied through a filter 33 to a No. 1 amplifier 37. The output of the No. 1 amplifier 37 is applied through a filter 41 to an antenna 45. The output of No. 2 modulator 29 is applied through a filter 35 to a No. 2 amplifier 39. The output of the No. 2 amplifier 39 is applied through a filter 43 to the antenna 45.

The operation of the transmitter is as follows: If key 1 is momentarily closed, the output from buffer 7 is impressed upon modulator No. 2 in which the outputs of the oscillator 21 and the master oscillator 31 are combined, that is, the derived current is of side band frequencies, (f_0+f_1) and (f_0-f_1) . Currents of frequency (f_0-f_1) pass through the filter 35, are amplified and radiated from the antenna 45. At the same time, currents of frequency f_3 from buffer 11 are applied to modulator No. 1 where they are combined with currents of frequency f_0 to form currents of frequencies (f_0-f_3) and (f_0+f_3) . This current (f_0+f_3) is passed through the filter 33, the amplifier 37 and the network 41, and is also radiated by the antenna 45. The networks 41 and 43 keep the impulses of different frequency from combining in the output circuits of the amplifiers. Thus in the system described, impulses of two different frequencies are simultaneously radiated by using keys or switches of the snap contact type to control the transmitter. The pulses are preferably made of very short duration, by way of example, of the order of a few milliseconds.

In the event that either of the other keys 3, 5 are operated, another pair of impulses of a different frequency combination will be simultaneously radiated. Thus, three different combinations of pulses operated at different frequencies are arranged so that they may be radiated in distinctive pairs. It is preferable that no pair of pulses have the same sum frequency or the same difference frequency as any other pair. By applying this rule for the selection of frequencies, greater freedom from interference and deciphering is experienced. High amplifier efficiency may be maintained by transmitting only one signal at a time through each ampli-

fying channel. Using three modulating frequencies f_1 , f_2 and f_3 , there are fifteen possible pair combinations, but, of these fifteen, only two groups of three pair are within the rule of the maximum safety from deciphering and at the same time permit the amplifiers to operate most efficiently. The other nine possible combinations may be used if safety and efficiency are unimportant.

10 In order that a given combination be made as difficult to decipher as possible, the available safe combinations may be varied by employing one or more keying arrangements, as represented in Fig. 1, or the alternative arrangement shown 15 in Fig. 2. In Fig. 2, the first key 1 is connected to the second 13 and fifth 19 buffers; the second key 3 is connected to the first 7 and fourth 17 buffers; and the third key is connected to the third 15 and sixth 11 buffers. The remainder 20 of the circuit corresponds to the circuit of Fig. 1. If different combinations are used at the transmitter, it should be understood that a corresponding change is required at the receiver in order that the same keys control the same functions.

25 The detailed connections for each oscillator and its connected buffers are shown in Fig. 3. The triode portions of a pair of thermionic tubes 51, 53 are connected, in parallel, to a piezoelectric crystal 55 and maintain it in continuous oscillation. Grid electrodes, regulating the electronic coupling from the triode sections, are keyed by the switches 4, 5 which correspond to the keys previously described. Connections are also made to the other oscillator buffers, as are indicated by the leads 51, 59. The output connections preferably include resonant circuits 61, 63 which are coupled, respectively, to modulators No. 1 and No. 2, as shown in Fig. 1. A recycle switch 64 is connected in the C battery lead to 30 permit the switching devices to be reset if the devices become misarranged by the omission of a cycle, or the like.

35 The master oscillator and modulator circuit connections are shown in Fig. 4. The master oscillator is preferably controlled by a crystal 65, which may be arranged to oscillate at its third harmonic, 15 megacycles per second, near which frequency the network 67 is resonant, and the 40 harmonic frequency may be doubled in the output circuit of thermionic tube 69. The output currents are applied in push-pull to the grids of the balanced modulators 71, 73. The input from the buffer stages of one set of modulating oscillators is applied through a mutual coupling 45 75 to the resonant circuit 77, which is connected to control grids in thermionic tubes 71, 73 in push-pull. The parallel-connected anode circuits of these tubes include a resonant circuit 79 which is suitably coupled through the filter 35 to the second amplifier 39, as shown in Fig. 1. A 50 second balanced modulator including thermionic tubes 81, 83 is connected in parallel to the first balanced modulator 71, 73. The input from the 55 oscillator buffers is applied to a resonant circuit 85 which is connected to control grids in the thermionic tubes 81, 83. The anode or output circuit of the thermionic tubes includes a resonant circuit 87 which is coupled through the filter 33 to the first amplifier 37, as shown in Fig. 1.

70 The radio receiving device is schematically illustrated in Fig. 5. An antenna 101 is connected to a first radio frequency amplifier 103. The first amplifier is responsive to a range of frequencies corresponding to the frequencies of

one group of transmitted impulses f_0+f_1 , f_0+f_2 , and f_0+f_3 corresponding, by way of example, to 5 32.00, 32.01 and 32.02 megacycles per second. The output from the radio frequency amplifier 103 is impressed upon a modulator 105 which is connected to a local oscillator 107. This local oscillator is preferably operated at the same frequency f_0 as the master oscillator in the transmitter. The local oscillator may be operated at any suitable frequency provided it is constant 10 with respect to the transmitter and the balance of the equipment is designed to accept or reject, respectively, currents of the desired or undesired frequencies. The output from the modulator 105 is connected to an intermediate frequency amplifier 109 which is responsive to a 15 range of frequencies extending from f_1 to f_3 . The output from the intermediate frequency amplifier is applied to three filters 111, 113, 115. These filters are respectively responsive to the 20 frequencies f_1 , f_2 , f_3 . The outputs of the three filters are applied to one of the input circuits of rectifier and locking devices 117, 119 and 121, which will be hereinafter described.

25 The antenna is also connected to a second radio frequency amplifier 123, which is responsive to the lower of the transmitted frequency groups, for example, 27.98 to 28.00 megacycles per second. The output of the second radio frequency amplifier is connected to a modulator 125 which is connected to the local oscillator 107. The modulator output is applied to a second intermediate frequency amplifier 127 which is responsive throughout the frequency range f_1 to f_3 . The second intermediate frequency amplifier 30 is connected to filters 129, 131, 133, which 35 respectively pass currents of the frequencies f_1 , f_2 and f_3 . The outputs of the last-mentioned three filters are applied respectively to the input of the rectifier and lock devices 117, 119 and 121. 40 The outputs of the rectifier and lock devices are applied to toggle circuits 135, 137 and 139, which will be hereinafter described. The output from the toggles may be applied to relays or other devices whose function is to be controlled by the 45 transmitted pairs of impulses. Connections of the pairs of filters of the two channel groups to the function controlling devices 135, 137, 139 must correspond to those from the function-selecting switches 1, 3, 5 to the buffers of the two channel 50 groups at the transmitter.

55 The rectifier, lock and toggle devices are represented by the schematic circuit diagram of Fig. 6. The filter inputs are applied through capacitors 136, 138 to a pair of control electrodes 140, 142 of a thermionic tube 141. The control electrodes are connected respectively to a C battery through resistors 144, 146. The values of resistance and capacitance are preferably so chosen that their respective time constants will be of 60 the order of the impulse duration, and so that impulses of less than half normal duration will not cause operation of the rectifier and lock. The rectifier and lock tube is so biased that it requires the simultaneous application of the two 65 transmitted impulses to permit rectification within the tube. The rectified signals are derived in the output circuit and are applied to the input circuits of a pair of tubes 143, 145. These tubes are so connected that a steady current flows only 70 in the output circuit of one of these tubes at a time, depending upon the application of potentials to their input circuits. In effect, the tubes 143, 145 operate as a toggle. The theory of their operation is substantially that of the multivi- 75

brator except that they are not self-oscillatory but aperiodic and operate only upon the application of triggering impulses. The toggle device is described in U. S. Patent No. 2,050,059 which 5 issued to W. R. Koch on August 4, 1936, and is assigned to the same assignee as the instant application.

The theory of operation of the receiving system is as follows: The simultaneously transmitted pairs of impulses are received and amplified, respectively, in the first or second radio frequency amplifier, depending upon the frequency of the received impulses. The amplified currents are converted from currents corresponding 10 to upper and lower side band frequencies into currents of intermediate frequency which correspond to the transmitter oscillator frequencies f_1 , f_2 or f_3 . The intermediate frequency currents will be passed by the filter corresponding 15 to their original frequency and rejected by the other filters. Thus, there will appear in the output of the filters currents of two frequencies corresponding to f_1 , f_2 or f_3 . Depending upon 20 their frequency, these currents will be simultaneously applied to one of the rectifier and lock devices. The rectifier and lock device which is operated by any particular pair of impulses will correspond to one of the snap keys 1, 3 or 5. The output currents may be used to actuate a 25 relay in either the operative or inoperative position or in either of two operative positions. It should also be understood that the derived currents may be used to actuate a step-by-step relay in place of the electronic toggle, if sequential rather than alternate on and off control of 30 any function be desired, or any suitable instrument for controlling the several functions.

Thus, the invention has been described as a remote radio control in which a pair of impulses of different frequency are simultaneously transmitted. The received pulses depending upon their respective frequencies are used to selectively control a locking device which is only responsive to the two particular frequencies 45 when they are simultaneously applied. The locking device in turn controls a relay which governs the function to be remotely controlled. It should be understood that the invention is not limited to the control of three functions as the 50 same system may be expanded to include a larger number of operations; in fact, one of the practical advantages of the invention, economy of apparatus, is only fully realized when a considerable number of functions are controlled. 55 It should also be understood that while two simultaneously transmitted pulses of unrelated frequencies are used to provide safety from deciphering, the system may be made even more safe by using three or more simultaneous pulses 60 of unrelated frequencies. It is apparent that it will be difficult to decipher the operation of the device because the controlling radio waves are of many different frequencies and each is only radiated for a very brief interval which makes 65 analysis most difficult. Furthermore, the frequency of the controlling pulses is continuously changing in what may be a very large number of different combinations. It is desirable to use interlocked switches or keys at the transmitter 70 to prevent simultaneous transmission of undesired combinations of impulses. The interlocking may be accomplished by mechanical or electrical means.

One form of mechanical interlock for the keys 75 1, 3, 5 is shown in Figs. 7 and 8. The key knobs

151, 153, 155 are provided with shafts 157, 159, 161 which include bulging portions 163, 165, 167. These portions pass freely through aligned apertures in fixed plates 169, 171. A slideable plate with separable sections 173 is arranged within 5 the fixed plates. The apertures in the slideable plate are offset so that only one aperture in the slideable plate will be aligned with a pair of aligned apertures in the fixed plates by the movement of the bulged portion (for example, 10 portion 165) of any one shaft. The misalignment of the remaining apertures in the slideable plate prevent the operation of the remaining keys until the operated key (for example, key 153) has been released. 15

I claim:

1. In a control system means for transmitting a pair of impulses of different frequencies, means for receiving said impulses, rectifying means responsive only upon the simultaneous application 20 of said pair of impulses for deriving from said pair a single impulse, and means responsive to said single impulse.

2. In a radio remote control system means for radiating a pair of impulses of different frequencies, means for receiving said impulses, means solely responsive to the simultaneous application of said pair of impulses for separating said impulses, means for rectifying said separated impulses to derive therefrom a single rectified impulse, and means responsive to said single impulse to effect said control. 30

3. In a radio remote control system means for radiating simultaneously a pair of radio impulses of different frequencies, means for separately receiving said impulses, a rectifier and lock device, means for simultaneously applying said received pair of impulses to said rectifier and lock device to derive therefrom a single controlling impulse, and means for applying said 40 single impulse to a device to be controlled. 35

4. In a remote control system a transmitter, means for deriving from said transmitter impulses of short duration and different frequency, means for transmitting said impulses, means for 45 receiving and separating said impulses, a rectifier including locking means, said locking means being so constructed and arranged that said rectifier responds only upon the simultaneous application of said impulses of different frequency, 50 means for applying said separated impulses to said rectifier and locking means and deriving therefrom single controlling impulses, a toggle device for alternately starting and stopping current flow in accordance with the application 55 of successive ones of said controlling impulses, and means for utilizing said currents.

5. In a remote control transmitter means for generating impulses of a plurality of different frequencies, a pair of balanced modulators, a 60 master oscillator connected to said modulators, means for applying simultaneously two of said impulses to said balanced modulators, respectively, to therein modulate said master oscillator, means for deriving simultaneously from said balanced modulators respectively impulse currents corresponding to an upper and a lower side band frequency, and means for transmitting simultaneously said last-mentioned impulse currents. 65

70 75 7. In a remote control receiver means for receiving separately impulses of different frequencies, a local generator of oscillations, a pair of modulators connected to said oscillator, means for applying two of said separated impulses to

- 5 said modulators respectively to therein modulate said local oscillations, means for deriving from said modulators two impulse currents of different frequencies, a rectifier and locking device, means for applying said last-mentioned currents to said rectifier and lock to derive from two simultaneously applied pulses a single rectified pulse, and means responsive to said single impulse for controlling a selected function.
- 10 7. In a remote control system means for generating impulses of a plurality of different frequencies, a pair of balanced modulators, a master oscillator connected to said modulators, means for applying two of said impulses to said balanced modulators respectively to therein modulate said master oscillator, means for deriving from said balanced modulators respectively impulse currents corresponding to upper and lower side band frequencies, means for transmitting 15 said last-mentioned impulse currents and a receiver including means for receiving separately impulses of different frequencies, a local generator of oscillations, a pair of modulators connected to said oscillator, means for applying two 20 of said separated impulses to said modulators respectively to therein modulate said local oscillations, means for deriving from said modulators two impulse currents of different frequencies, a rectifier and locking device, means for applying said last-mentioned currents to said rectifier and lock to derive from two simultaneously applied pulses a single rectified pulse, and means responsive to said single impulse for controlling a selected function.
- 25 8. The method of remote control which includes transmitting impulses of different frequencies, receiving said transmitted impulses, simultaneously rectifying said impulses to derive a single controlling impulse, limiting the rectification to the simultaneous application of said impulses, and applying said controlling impulse to operate a selected function.
- 30 9. The method of transmitting remote control impulses which includes generating a pair of impulses of different frequencies, modulating 35

simultaneously said impulses with a current of another frequency to obtain impulse currents of the modulation frequencies, deriving simultaneously from said currents of modulation frequencies impulses of frequencies corresponding to upper and lower side band frequency, and transmitting simultaneously said last-mentioned impulses.

10. The method of receiving remote control impulses of different frequencies which includes 10 separately receiving said impulses, generating local oscillations, modulating said local oscillations by said received impulses, deriving from said modulations separated impulse currents of different frequencies, simultaneously rectifying 15 said currents to obtain a single impulse current, and applying said single impulse current to control a function.

11. The method of remote control by impulses which includes generating a pair of impulses of 20 different frequencies, modulating said impulses with a current of another frequency to obtain impulse currents of the modulation frequencies, deriving from said currents of modulation frequencies impulses of frequencies corresponding 25 to an upper and a lower side band frequency, and transmitting said last-mentioned impulses, separately receiving said impulses of upper and lower side band frequency, generating local oscillations, modulating said local oscillations by 30 said received impulses, deriving from said modulations separate impulse currents of two different frequencies, simultaneously rectifying said currents to obtain a single impulse current, and applying said single impulse current to control a 35 function.

12. In a system of the character of claim 1, means for interlocking said transmitter to prevent transmission of other than the desired impulses.

40 13. In the method described by claim 8, the additional step of preventing transmission of other than the desired impulses.

DAVID G. C. LUCK. 45
